DESIGN FOR A DRESS ENSEMBLE

Alfred O. Gilbert, Chicago, Ill.

Application November 26, 1940, Serial No. 96,847

Term of patent 3½ years

To all whom it may concern:

Be it known that I, Alfred O. Gilbert, a citizen of the United States, residing in Chicago, in the county of Cook and State of Illinois, have invented a new, original, and ornamental Design for a Dress Ensemble, of which the following is a specification, reference being had to the accompanying drawing, forming part thereof.

Figure 1 is a front view of a dress ensemble, showing my new design;

Figure 2 is a rear view of Figure 1;

Figure 3 is a fragmentary front view of the upper portion of the dress member of the ensemble shown in Figure 1;

Figure 4 is a rear view of Figure 3; and

Figure 5 is a detail view illustrating the spool and needle closure means for the front of the jacket.

The characteristic feature of my design resides in the combination on the ensemble disclosed of the jacket member which is yoked and seamed as shown, and having a spool and needle closure means on the front thereof.

I claim:

The ornamental design for a dress ensemble, substantially as shown and described.

ALFRED O. GILBERT.
